BY *Victor J. Evans*

WITNESS:

ATTORNEY

UNITED STATES PATENT OFFICE.

BAYARD T. MERRILL, OF VALSETZ, OREGON.

HEADLIGHT.

Application filed April 12, 1924. Serial No. 706,173.

To all whom it may concern:

Be it known that I, BAYARD T. MERRILL, a citizen of the United States, residing at Valsetz, in the county of Polk and State of Oregon, have invented new and useful Improvements in Headlights, of which the following is a specification.

This invention relates to headlights for motor operated vehicles, and aims to simplify the construction illustrated and described in Patent #1,248,146, issued to me on November 27, 1917, the invention having for its object, a headlight construction designed to prevent the light rays from being directed upwardly above a predetermined point, and thus prevent collisions and accidents usually resulting from the blinding effect these rays have on pedestrians and drivers of other automobiles.

In carrying out the invention, I provide a construction wherein the light rays are directed outwardly and downwardly for the proper illumination of the roadway in advance of the vehicle, and eliminates all upwardly directed rays with their resultant blinding effect upon the eyes of the others, and accomplishes these ends without the necessity of dimming the lights, which practice is now commonly resorted to for this purpose.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a front elevation of the headlight constructed in accordance with the present invention.

Figure 2 is a sectional view taken on the line 2—2 of Figure 1.

Referring to the drawings in detail, 10 represents what I term the main reflector of the headlight, and from an inspection of Figure 2, it will be noted that the lower end of this reflector projects an appreciable distance forward or in advance of the upper edge thereof, so that the auxiliary reflector 11 is permitted to be arranged at a peculiar

angle with relation to the upper edge of 55 the reflector 10 and the adjacent edge of the lens 12. The auxiliary reflector 11 is of course constructed from any suitable opaque material, and the line of projection indicated at X intersects the apex or point 60 of juncture between this auxiliary reflector 11 and the lens 12. It will be noted from an inspection of Figure 2 that the projection point is arranged in the line X, 65 which line is directed outwardly and downwardly, from the bulb 13 supported by the reflector 10 at a point above the lower edge of the opaque auxiliary reflector 11. Consequently, the projection point Y is 70 disposed above the center of the front of the headlight, and this fact coupled with the particular location of the bulb 13, prevents the light rays from being directed upwardly, with the detrimental results 75 above pointed out. On the contrary the light rays are directed outwardly and downwardly at such an angle with relation to the ground, as to properly illuminate the latter the requisite distance in advance of 80 the machine, and at the same time eliminate any blinding effect on pedestrians and drivers of other vehicles, which is accomplished without dimming the lights or in any other way manipulating the same. 85 The lower end of the reflector is formed with a semi-circular flange 14 which bears against the adjacent portion of the lamp casing, to assist in supporting the reflector in position, cooperating with the top portion of the reflector for this purpose, which 90 top portion contacts the adjacent wall of the casing as illustrated in Figure 2.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

An automobile headlight comprising a casing, a reflector arranged therein and including a curved body portion having an opening at a point above its transverse center to receive and support an electric light bulb at a downward inclination with

respect to said casing, the forward edge of the reflector terminating to provide a semi-circular flange projecting outwardly therefrom and arranged to engage the adjacent wall of the casing, the upper portion of the reflector contacting the adjacent wall of the casing, and a shield of opaque mate-

rial projecting outwardly and downwardly from the remaining upper half of the reflector, and terminating at a point in a plane beneath said bulb as and for the purpose specified. ¹⁰

In testimony whereof I affix my signature.

BAYARD T. MERRILL.
